UNITED STATES PATENT OFFICE.

ADALBERT D. JOSEPHSON, OF NEW YORK, N. Y.

DESIGN FOR A BUTTON-DISPLAY CARD.

53,202.

Specification for Design.

Patented Apr. 15, 1919.

Application filed January 30, 1919. Serial No. 274,150. Term of patent 14 years.

To all whom it may concern:

Be it known that I, ADALBERT D. JOSEPHSON, a citizen of the United States, residing at New York city, in the county and State of New York, have invented a new, original, and ornamental Design for Button-Display Cards, of which the following is a specification, reference being had to the accompanying drawing, forming a part thereof.

The figure is an elevational view of a button display card showing my new design.

I claim:

The ornamental design for a button display card, as shown.

ADALBERT D. JOSEPHSON.

Witnesses:

CLARICE FRANCK,
SYLVIA LEOPOLD.
